UNITED STATES PATENT OFFICE.

GEORGE A. SMALL, OF JEFFERSONVILLE, ASSIGNOR TO JOSIAH BETTIS, OF NEW ALBANY, INDIANA.

CAR-BRAKE.

SPECIFICATION forming part of Letters Patent No. 289,314, dated November 27, 1883.

Application filed April 18, 1882. (No model.)

To all whom it may concern:

Be it known that I, GEORGE A. SMALL, of Jeffersonville, in the county of Clarke and State of Indiana, have invented certain new and useful Improvements in Car-Brakes; and I do hereby declare the following to be a full, clear, and exact description of the invention, such as will enable others skilled in the art to which it pertains to make and use the same.

5 My invention relates to car-brakes; and it consists in the peculiar construction and attachment of a brake-rod to a car platform or frame, whereby it is adapted to be changed from a vertical to a horizontal position, and vice versa, as will be hereinafter fully set forth and claimed.

10 In the drawings, Figure 1 is a plan view of a portion of a car-platform, showing my brake-rod attached. Fig. 2 is an end view, and Fig. 20 3 is a side elevation, of the same. Fig. 4 is a vertical section taken through Figs. 1 and 2, line $x x$. Fig. 5 is a plan view of the hinged journal used for supporting the brake-rod in a vertical position.

15 A is a car-platform. B is a brake-rod, which is provided with a ratchet-wheel, C.

D is a pivoted journal, through which the rod B passes, and in which the said rod is journaled.

20 E is a curved guide. One end of the guide is secured to the lower end of a bracket, F, and the other end is secured to the car-platform A. This guide E acts to guide and support the lower end of the brake-rod B, and at 25 the same time to allow the said end to slide between its sides.

G is a hinged journal, which acts to support the rod B in an upright or vertical position, as shown by dotted lines, Fig. 2. This sup-

30 port may be formed in any suitable manner, the preferred form being that illustrated in Fig. 5, the same consisting of a hinged journal, G, secured to the end of the car A, and acting to support the rod B in an upright or

45 vertical position, as shown by the dotted lines in Fig. 2. This journal consists of a shelf, g, having a slot, g' , which is adapted to receive the brake-rod B. A curved arm, g'' , is pivotally secured at one end to the shelf, the other

50 end being provided with an eye adapted to re-

ceive the pin g'' , said pin also passing through an opening in the shelf, thus securing the brake-rod when in a vertical position.

H is a hook, in which the rod B rests when it is in a horizontal position, as shown in Figs. 55 1 and 2.

I represents the pawl which is generally used on cars in connection with vertical brake-rods, which, by engaging with the ratchet-wheel thereon, acts to prevent the rod B from 60 revolving when the brakes are set. To provide for the brake-rod being held from revolving when it is in a horizontal position and the brakes are set, I provide a peculiar pawl, which consists of a rod, J, provided with 65 two arms, a and b , set at right angles to the body of the rod, and also at an angle one to the other, one arm, b , acting as a pawl, and the other arm, a , acting as a weight to hold the pawl engaged with the ratchet, as shown 70 in Figs. 2 and 3, or out of engagement, as shown by dotted lines, same figures.

The operation of my device is as follows: The brake-chain is attached to the brake-rod B at a point above the guide E. The wheel 75 at the upper end of the rod B is turned, and operates to revolve the rod B and wind the chain thereon, the rod being held from turning in the opposite direction by means of the pawl I when the rod is in a vertical position, 80 and by means of the pawl a on the rod J. The rod is changed from a vertical to a horizontal position by releasing it (the rod B) from the hinged journal G and turning it toward the hook H and letting it rest therein. This changing of the brake-rod B is desirable when the car is loaded with lumber or like freight, when 85 the said rod would be liable to become broken off or bent.

What I claim is—

1. A brake-rod provided with suitable 90 bearings and adapted to be arranged for operation in both vertical and horizontal positions, substantially as set forth.

2. The combination, with a brake-rod adapted to be changed from a vertical to a horizontal position, of a curved guide adapted to guide and support the end of said brake-rod, substantially as described.

3. The combination, with a brake-rod adapt- 100

ed to be changed from a vertical to a horizontal position, of a pivot provided with a head, through which said rod passes, whereby said rod is adapted to be changed from a vertical to 5 a horizontal position, substantially as and for the purpose shown and described.

4. The combination, with a brake-rod adapted to be changed from a vertical to a horizontal position, of the rod J, provided with arms to a and b, and adapted to act as a pawl when

the rod is in a horizontal position, substantially as and for the purpose shown and described.

In testimony whereof I have signed my name to this specification in the presence of two sub- 15 scribing witnesses.

GEORGE A. SMALL.
